UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

ANTIFRICTION BEARING

Application filed February 5, 1926. Serial No. 86,160.

This invention relates to anti-friction bearings.

One object of the invention is to provide a simple, practical and efficient anti-friction bearing, especially adapted for railway car side bearings, in which the parts are so arranged that the anti-friction element is automatically returned to normal centered position when free from load.

Another object of the invention is to provide a side bearing including a retainer provided with an adjustable bearing plate upon which an anti-friction element is adapted to move to either side of central position, together with centering means which yieldably operate to return said anti-friction element to central position when free from load, and which serve to maintain said element in assembled relation with said retainer, said centering means being detachable to permit removal of said antifriction element and gain access to the bearing plate for the purpose of adjusting the same.

Other and further objects of the invention will more clearly appear from the description and claims hereinafter following.

In the drawings, forming a part of this specification, Fig. 1 is a vertical sectional view taken through the ends of the body and truck bolsters of a railway car, showing my invention in connection therewith in vertical section. Fig. 2 is a top plan view of the bearing illustrated in Fig. 1, showing the same detached from the truck bolster. And Fig. 3 is a transverse vertical section of the bearing taken substantially upon the line 3—3 of Fig. 1.

In said drawings 10 denotes the underside of the body bolster and 11 the upper side of the corresponding truck bolster of a railway car. The improved side bearing is shown as applied to the truck bolster and comprises broadly a mounting or retainer A; and adjustable bearing plate B, an anti-friction element C; and centering means D.

As shown in the drawings, the housing or retainer A comprises a generally boxlike member having side walls 20—20 and end walls 21—21, and a bottom 22, the bottom being provided with upstanding extensions

23—23 providing a central compartment 24 for the bearing plate B. The side walls 20—20 of said housing are inwardly offset toward each other as indicated at 25—25 to provide at each side of the housing on the interior thereof, oppositely disposed abutments 26—26 and 27—27. The end walls 21—21 of the housing are vertically arranged and are similar except for their opposite disposition, each of said end walls being provided with a semi-circular chamber 28 open at the top, formed by offsetting each end wall outwardly as indicated at 29, the inner face of the end wall of each offset being provided with a rounded protuberance 30 adapted for cooperation with the centering means as herein-after described. The housing A also is provided with laterally extending lugs 31—31 adjacent the opposite ends through which may be extended rivets 32—32 which serve to secure the housing A to the truck bolster plate 11.

The adjustable bearing plate B comprises a bearing plate proper indicated at 33, and a plurality of shims 34 upon which the bearing plate 33 rests, the bearing plate and shims being of a size so as to fit snugly in the central compartment 24 provided therefor.

The anti-friction element C, as shown, is in the form of a cylindrical roller adapted to roll upon the bearing plate 33, said roller being of slightly less width than the distance between the inset portions 25—25 of the side walls.

The centering means D comprise a saddle 35, followers 36—36, resilient or yieldable means 37—37, and detachable connecting members or housings 38—38. The saddle 35 is of rectangular formation having side portions 39—39 and end portions 40—40, the end portions 40 each having a curved face which engages the anti-friction element C above the central axis thereof as indicated at 41, the end portions 40 below the curved faces being vertically arranged as indicated at 42. Each end portion 40 of the saddle 35 is provided on its outer face with a centrally disposed horizontally extending hollow boss 43, which projects from the end portion 40

100

a suitable distance. Both end portions of the saddle 35 are similar and the same numerals will be utilized for designating similar parts.

Mounted upon the hollow boss 43 at each 5 side of the saddle is one of the followers 36. Each follower is provided with a central opening for the reception of the boss 43, the forward face of the follower abutting the rear face of the end portion 40 of the saddle. 10 The rear face of the follower is provided with a hollow cylindrical extension 44, the inner diameter of the extension 44 being somewhat greater than the exterior diameter of the boss 43, the external diameter of the extension 44 15 being of such extent as to slidably fit within a cylindrical recess 45 formed in the connecting member or housing 38. The exterior contour of the housing or connecting member 38 is such as to fit snugly within the chamber 28 20 of the retainer, the housing being provided at its rear face with a rounded socket 46 adapted to accommodate or interengage with the projection 30 upon the adjacent end wall of the retainer. The inner surface of the end wall 25 of the housing 38 is provided with a boss 47, and mounted upon the boss 47 and upon the hollow boss 43 on the saddle is a coiled spring 37, said spring at its end bearing upon the follower 36, and at its outer end bearing upon the end wall of the connecting member or 30 housing 38. The construction of the centering means at both ends of the bearing are identically similar and the same reference 35 characters will be utilized to designate like parts of both.

In operation, assuming the anti-friction element C to be moving under load toward the right as viewed in Fig. 1, the saddle 35 will 40 be carried therewith, moving the follower 36 in the same direction of travel, which follower acts upon the spring 37 to compress the same against the rear wall of the housing or connecting member 38 which is in abutment 45 with the right hand end wall 21 of the retainer. During this action the spring at the left hand end of the housing, and the left hand follower, will be held from following the saddle by reason of engagement of the ends of 50 the follower with the abutments 26 and 27 on the side walls of the housing. The energy stored in the right hand spring will serve to return the anti-friction element to central position. Operation of the anti-friction element in the reverse direction will bring about 55 a reversal of the operation of the parts of the centering mechanism as will be understood.

When it is desired to adjust the vertical height of the anti-friction element C, it is 60 necessary only to compress the connecting members 38-38 toward each other sufficiently to permit the bosses 30 on the retainer to slide out of the sockets 46 in the end walls of the members 38-38, the entire centering 65 means being then removed, thus freeing the

roller, which may be then removed, and exposing the bearing plate in such manner that shims may be inserted or removed from beneath the same so as to adjust the vertical height of the bearing plate 33, after which 70 the roller may be replaced in position, and the entire centering means assemblage reinserted into the retainer and pressed downwardly until the bosses 30 again reengage with the sockets 46 of the housings 38-38, after which 75 the roller will be maintained in central position when free from load and retained in assembled relation with respect to the retainer by reason of engagement of the saddle at points on the anti-friction element above the 80 central axis thereof, the difference in height of the anti-friction element due to the change in adjustment of the vertical height of the bearing plate being accommodated by the relative vertical movement of the roller with reference to the saddle.

By the above described arrangement it will be appreciated that an adjustable bearing plate is provided permitting adjustment of the vertical height of the roller, and that centering means are utilized which are insertable and detachable with reference to the retainer as an assemblage, and when in operative position not only return the anti-friction element to centered position when free from load, but maintain the same in assembled relation with the bearing.

While I have herein shown and described what I now consider the preferred manner of carrying out the invention, the same is merely 100 illustrative, and I contemplate all changes and modifications that come within the scope of the claims appended hereto.

I claim:

1. In an anti-friction bearing, the combination with a mounting; of an adjustable bearing plate associated with said mounting; an anti-friction element adapted to move back and forth upon said bearing plate; and means for centering said element when free from load including spring followers, spring abutment elements, and springs interposed between said abutment elements and said followers, said centering means being bodily removable as a unit from said mounting; and co-operating means on said abutment elements and mounting held engaged by said springs for holding the parts assembled.

2. In an anti-friction bearing, the combination with a mounting; having anchoring means thereon, said mounting being provided with a bearing plate; of anti-friction element movably mounted on said bearing plate; and centering mechanism for said anti-friction element adapted to maintain said anti-friction element in assembled relation with said mounting, said mechanism including abutment members and yieldable means, said abutment members engaging the anchoring means to hold the mechanism operatively as

sembled, and said yielding means engaging the abutment members to hold said members engaged with the anchoring means to lock said members to the mounting.

5 3. In an anti-friction bearing, the combination with a mounting; of an anti-friction element adapted to move back and forth on said mounting; centering means for said anti-friction element, said centering means including a saddle fitting over said anti-friction element, abutment members at opposite sides of the saddle and connecting elements between said saddle and abutment members, and spring means between said abutment 10 members and saddle; and means for detachably connecting said abutment members to said mounting, said saddle having means thereon telescopically engaging with said connecting elements, and said connecting elements being telescoped with said abutment members.

4. In an anti-friction bearing of the character described, the combination with a retainer provided with a bearing surface, of 25 an anti-friction element adapted to move back and forth on said bearing surface; of followers disposed at either side of said anti-friction element; of yieldable means interposed between said followers and means on 30 said mounting whereby said yieldable means bear against said followers; a saddle fitting over said anti-friction element and having 35 slideable engagement with said followers; and stops associated with said mounting and adapted to permit movement of each of said 40 followers in one direction, and prevent movement thereof in the opposite direction.

5. In an anti-friction bearing, the combination with a retainer provided with side and 45 end walls, said side walls being inwardly offset to provide abutments, and the end walls being offset to provide recesses; a vertical adjustable bearing plate; an anti-friction element adapted to move back and forth with respect to said retainer upon said bearing plate; a saddle fitting over said anti-friction element; followers slidably mounted with respect to said saddle, said followers being adapted to cooperate with the side wall abutment of said bearing to limit inward movement of said followers; housings arranged 50 at opposite sides of said anti-friction element, said end walls and said housings having interengaging parts detachable when moved in one direction; and resilient means interposed between each of said followers and the related housing, said resilient means operating to center said element when free from load and to maintain the inter-engaging 55 means between said housings and the end walls of said retainer in operative relation.

6. In an anti-friction bearing, the combination with a mounting provided with a bearing surface, said mounting having spaced 60 abutment means thereon; of an anti-friction

element movably supported on said bearing surface between said abutment means; and means for centering said anti-friction element and holding the same assembled with the mounting, including a member embracing the anti-friction element and engaging the same at opposite sides, a spring follower, an abutment member interposed between each abutment means and the anti-friction element embracing member, and spring means 70 interposed between each spring follower and the corresponding abutment member, each spring follower and corresponding abutment member having interengaging means thereon to prevent displacement of the same relative 75 to each other in a vertical direction, said spring follower and anti-friction element embracing member being interengaged to prevent relative vertical displacement thereof, said abutment members having shouldered 80 engagement with the abutment means of the mounting and being yieldingly held in engagement by said spring means to prevent vertical removal of the abutment members, said means for centering the anti-friction element and holding the same assembled with the mounting being bodily removable from the housing upon displacement of said abutment members toward each other and disengaging the abutment members from the abutment means, thereby permitting removal of the anti-friction element.

7. In an anti-friction bearing, the combination with an anti-friction element; of a container for said element relatively to which 95 said element is movable; means for retaining said element within the container, including a set of detachably connected housings at each side of said element, one housing of each set having a seat and said container having 100 retaining projections engaging respectively within the seats of the housings; and yielding means within each set of housings for forcing the same apart and holding the projections engaged with the seats to maintain 105 the housing assembled with the container.

8. In an anti-friction bearing, the combination with a support adapted to be secured to a railway car bolster, said support having a bearing surface; of an anti-friction element movable on said bearing surface; means for maintaining the anti-friction element assembled with the support, said means including centering means having engagement with the anti-friction element and holding the same against removal, anchoring members having shouldered engagement with the support, spring means 115 cooperating with said centering means and anchoring members for actuating the centering means and yieldingly holding the anchoring members in shouldered engagement with the support, and cooperating guide means carried entirely by said first named means for holding the parts thereof aligned and against 120 125 130

separation when assembled with the support,
said anchoring members being displaceable
against the resistance of the spring means to
permit disengagement of the anchoring mem-
bers from the support to allow bodily removal
as a unit of the means for maintaining the
anti-friction element assembled with the sup-
port.

10 In witness that I claim the foregoing I
have hereunto subscribed my name this 28th
day of January, 1926.

JOHN F. O'CONNOR.
